UNITED STATES PATENT OFFICE.

PATRICK GAVIN, OF BROOKLYN, NEW YORK.

NAILING MACHINE.

Application filed December 6, 1927. Serial No. 238,073.

This invention is a nailing machine for use more particularly in the laying of floors. Nailing machines have heretofore been used, some of which have been operated by power 5 and others of which are manually operative. The present invention relates to machines of the manually operated type.

Prior nailing machines of this character may be divided generally into two types, 10 namely, those wherein a plunger is operated by a mallet or hammer, so that the mallet or hammer held in the hand of the operator acts through a plunger to drive the nail after the manner of operating the nail set. 15 The other type of hand operated nailing machines generally embodies a relatively short plunger provided at its upper end with a knob or handle, whereby the plunger may be manually reciprocated to strike the nail a 20 succession of sharp blows. In machines of the last mentioned type, the plungers operate within a tube or guide which is relatively short, and the workman in operating these devices generally kneels, or moves 25 along the floor on his knees, manually reciprocating the plunger a plurality of times for the driving of each nail. Moreover, these devices generally are only used for the driving of relatively light or finishing nails and 30 are of no utility whatever for driving the heavier headed nails.

The object of the present invention is to provide a construction which overcomes the mechanical defects and disadvantages in 35 numerous prior devices of which I am aware, and which also enables the nail to be driven in one blow without the use of a hammer or mallet and by an operator in a standing posture. In operating the machine of the 40 present invention, the operator may walk about in upstanding position directing the machine before him and manipulating the plunger to drive the nails in one stroke. The machine of this invention will drive large 45 floor nails, as well as smaller finishing nails and may be used in the building art generally where a powerful and efficient nailing machine is needed.

In its preferred practical form, the machine of this invention embodies an upstanding tube supported in upright position on casters to enable it to be readily moved about and mounted for vertical reciprocation in this tube is a plunger of considerable 55 weight. This plunger is tall enough to be

readily grasped and operated by a man in standing posture, and, in practice, may conveniently be made about six feet in length. The tube need not be this long provided that above the tube and supported thereon is a 60 suitable guide for the plunger. The lower end of the plunger carries a driving pin which is demountably mounted on the plunger, so that it can be removed and replaced in the event that it becomes worn or burred and 65 to provide for driving pins of different sizes for nails of widely varying weight and style. The lower end of the tube is provided with a guide block mounted removably therein and capable of replacement to fit nails of different kinds or sizes. Nails are adapted to be automatically fed to the guide block from a magazine supported on the tube and guide to which I have referred, and the nails are positioned in this magazine to be fed one at 70 a time through a reciprocating valve or gate from whence they fall by gravity into position within the guide block. The magazine may be made in sections to facilitate positioning of the nails therein and is preferably 75 demountably positioned on the tube so that filling of the magazine may be more easily accomplished.

An important feature of the invention resides in the employment of a guide having 80 associated therewith means to engage with the foot of the workman, whereby the machine may be moved by the workman's foot and accurately guided thereby as the machine is moved along a floor.

Features of the invention, other than those specified, will be apparent from the herein-after detailed description and claims, when read in conjunction with the accompanying 90 drawings.

The accompanying drawings illustrate different practical embodiments of the invention, but the constructions therein shown, are to be understood as illustrative, only, and not as defining the limits of the invention.

Figure 1 shows a machine embodying the present invention partly in section and partly in elevation.

Figure 2 is an elevation of the machine 105 with certain parts shown in section.

Figure 3 is a section on the line 3—3 of Figure 1.

Figure 4 is a section on the line 4—4 of Figure 1.

Figure 5 is a section on the line 5—5 of Figure 1.

Figure 6 is a section on the line 6—6 of Figure 1.

5 Figure 7 is a section on the line 7—7 of Figure 1.

Figure 8 is an enlarged detail fragmentary plan view of guide and pointer mechanism shown in Figure 7.

10 Figure 9 illustrates the manner in which the machine may be guided by an attachment engaging with the shoe of the operator.

Figure 10 is a section perspective view of the nailing magazine shown in Figure 1.

15 Figure 11 is a similar view of a modified form of magazine.

Figure 12 is a section on the line 12—12 of Figure 11.

Referring to the drawings, 1 designates 20 the guide tube. This tube is thickened at its lower end to provide a strengthened seat and support for the guide block 2 which is removably seated in the lower end of the tube and normally locked in place by a set 25 screw 3. The guide block has a tapered mouth 4 leading to a cylindrical passage 5 in which the nails are adapted to rest in a position to be driven. A plunger 6 is mounted to reciprocate vertically in the tube and 30 is of a length to extend well above the top of the tube.

In the drawings, portions of this plunger are broken away, so that the plunger is fore-shortened, but, in practice, a plunger of 35 about 6 feet in length gives very satisfactory results. That portion of the plunger above the tube 1 is guided in a guide 7 rigidly supported by rods 8. These rods are secured by set screws 9 to collars 10 which 40 embrace the tube 1 as shown best in Figure 2. By this arrangement, the tube may be made relatively short and the plunger relatively long and while said plunger may be properly guided for vertical reciprocation. 45 The rods 8 also serve to support a bracket 11 mounted on the rods by set screws 12, as shown best in Figs. 2 and 3, and this bracket is provided at its outer end with an opening 13 which supports the upper end of the magazine as will hereinafter be more fully explained.

The lower portion of the tube is cut away at one side as shown at 14 to provide an opening in registration with which a diverging throat 15 is secured by means of bands or collars 16. These bands are secured in place by screws 17 which firmly bind the parts together, so as to normally mount the throat rigid with the tube.

60 A magazine 18 is adapted to rest upon the top of the throat member 15 as clearly shown in Figure 1, while the upper end of the magazine extends through the opening 13 in the bracket 11 which serves to steady and support such upper end. The magazine is pro-

vided near its lower end with perforations 19 (see Fig. 6) and spring actuated pins 20 are adapted to enter these holes when the magazine is in the position of Fig. 1 to secure the lower end of the magazine in alignment with the inlet of the throat member 15.

Cooperating with the upper portion of the throat member which is flared out laterally as shown in Fig. 6, is a valve or gate. This valve or gate embodies a rectangular frame 21. This frame may be made as shown in Fig. 5 with three sides rigid and the fourth side 22 held in place by nuts 23. The side 22 carries a finger 24 which extends through a hole in the wall of the throat and normally projects across the passage through said throat as shown in Fig. 1. The opposite side of the frame carries a finger 25 which also projects through the wall of the throat and slightly underlaps the end of the finger 24. The arrangement is such that when the magazine is charged with nails, they will gravitate into the positions shown in Figures 1 and 6 wherein the lowermost nail will rest flat upon the finger 24 which is preferably made fairly wide, so as to preclude tilting of the nail.

In order to feed nails in this manner to the valve or gate, the magazine is built as shown in Figs. 10 to 12, which illustrate two forms of construction. In both of these constructions, the nails are all positioned in the same vertical plane and in alternately reversed position, the magazine being provided with channels at its lateral edges to receive the nail heads and being of less width between these channels, so that the shanks of the nails are housed with a fairly snug fit.

In the arrangement of Fig. 10, one side wall 26 of the magazine is removable, so that when this wall is taken off the magazine may be laid down flat and the nails dropped into place and easily positioned therein. After the magazine is filled, the wall 26 is brought into position and secured in place and the magazine can then be placed on the machine and locked in place by the spring pins 20. To allow removal of the wall 26, this wall is provided with flanges 27 which are adapted to have interfitting relation with flanges 28 on the other section of the magazine, and tongues 29 formed on the flanges 28 extend thru slots in the flanges 27 and are perforated so that pins 30 can be passed through these flanges to hold the parts in assembled relation.

In the structure of Figs. 11 and 12, the walls of the magazine are rigid with respect to one another and nails are fed one at a time into the upper end of the magazine when it is desired to charge the magazine. It will be apparent that the arrangement illustrated in Fig. 10 is much more convenient and that the magazine may be more quickly filled with this latter arrangement.

than is possible with the structure of Figs. 11 and 12. In Fig. 11, nails 31 are shown in dotted lines as passed through the holes 19, to keep the nails from falling out of the 5 bottom of the magazine in the event that it is removed from the rest of the device for filling. These nails 31 are of course withdrawn after the magazine is filled and when it is positioned on the machine, so that the 10 spring pins 20 can engage with these holes to secure the magazine in position.

A filler blank 31^a may be employed in connection with the structures of Figs. 11 and 12 if desired. This blank is dropped into 15 the magazine before any nails are introduced and the nails are thereupon fed into the top of the magazine alternately and end for end and serve to force the filler blank downwardly until the magazine is completely 20 filled. The nails 31 are then removed and the filler blank 31^a is removed, whereupon the magazine may be mounted on the throat as described. The purpose of the filler blank is to preclude the nails from tilting, where- 25 by they are maintained with their shanks in parallel relation during the filling operation. The blank 31^a is substantially the same as a nail except that it is somewhat longer and has a head at both ends. These 30 heads engage with the nail head channels of the magazine so that it is impossible for the blank to tilt and consequently all the superimposed nails are precluded from tilting during the filling operation.

35 The structure of Figure 10 is filled while the magazine lays flat and it is not necessary to put the nails in the holes 19 as shown in Figure 11.

When the magazine is filled and the parts 40 assembled, the nails will gravitate into the position shown in Figs. 1 and 6 as described with the lowermost nail resting on the finger 24. It will be noted, however, that the frame 21 is provided with a socket or hole 45 32 and into this socket projects one arm of a bell crank 33, which is pivoted at its elbow on a lug on the throat member 15, while the other arm of the bell crank is secured to a rod 34. The rod 34 projects upwardly, is 50 guided through holes in the collars 10, and is secured to a trigger 35 which projects in the direction of the plunger 6. This trigger is also connected by a rod 36 to a bolt 37 mounted to move longitudinally through 55 the guide 7. This bolt has a head 38, so positioned as to be engaged at the proper time by a ring 39. This ring is mounted on the plunger and is secured thereon in proper adjustment by a set screw 40. Similarly the 60 trigger 35 is adapted to be engaged by a ring 41 held in adjustment by a set screw 42. When the plunger is elevated, the ring 39 strikes against the head 38, elevates the bolt 37 and draws the rod 36 upwardly. This in 65 turn draws the rod 34 upwardly and tilts

the bell crank 33 so as to move the valve into the normal position of Figs. 1 and 6. When the plunger is thereafter depressed, the ring 41 engages the trigger 35 and forces the rod 34 downwardly thereby tilting the bell 70 crank and moving the valve to the rod in Fig. 1, so that the lowermost nail is disengaged from the finger 24 and falls on to the finger 25 which by this movement extends across the passage of the throat. 75

Upon the next upward movement of the plunger and consequent engagement of the ring 39 with the head 38, the valve parts will be returned to the position of Fig. 1, but during this operation, the lowermost 80 nail which has been held by the finger 25 will be released and will fall through the throat. During this falling movement, it engages with a projection 43 which causes the nail to be tilted into upright position 85 whereupon the nail falls through the throat and is guided thereby to the passage in the guide block where it assumes the position shown in Figure 1. This nail is adapted to be driven upon the next downward move- 90 ment of the plunger 6 and for this purpose the plunger is provided at its lower end with a driving pin 44. This pin is preferably tapered so as to be introduced through the top of a holder 45 which is then 95 screwed into the lower end of the plunger to rigidly mount the driving pin in place. When the plunger descends, the driving pin drives the nail.

As stated, the plunger is relatively heavy 100 and when operated will serve to drive fairly heavy nails in one stroke and without any tendency to bend the nails. Both the driving pin and guide block may be removed and different sizes substituted when it is 105 desired to change the nail sizes.

The lower end of the tube is embraced by a ring 45 secured in position by a set screw 46 and this ring carries a plurality of spring arms 47 preferably three in number. On 110 the end of each spring arm is secured a caster 48 and these casters serve to properly support the device in upstanding position. The resilient arms 47 are sufficiently strong to normally support the lower end of the 115 tube free from the floor, so that it can be readily moved, but when the plunger is depressed, the weight of this plunger operating the trigger 35 and forcing the nail downwardly depresses the entire apparatus 120 against the resiliency of the spring arms, so that the lower end of the tube engages the floor at the instant when the nail is driven. As soon as the plunger is elevated, however, the device again lifts to allow of 125 free movement of the assembly. In order that the nailing may be carried on along the predetermined line, the device is preferably provided with a gage 49 extending radially therefrom as shown in Figures 7 and 9. 130

This gage may have an adjustable pointer 50, as shown in Fig. 8. In this figure, the edge of a board is indicated at 51 and 52 indicates a nail previously driven along one edge of the board. The pointer 50 serves to indicate the relation which the next nail driven will bear to the nail 52, so that lines of nails along the two edges of the board may be uniformly positioned. The guide 10 as shown is provided on its outer end with an upstanding pin 53. This is provided to engage a clamp 54 adapted to be secured to the shoe of the workman, as indicated in Fig. 9, so that by movement of the workman's foot, the machine may be guided and moved along the floor into the position desired.

The machine of this invention is simple in construction and thoroughly efficient in the 20 carrying out on its intended purposes. It will operate upon nails of widely varying sizes, as well as both headed and finishing nails, and will drive these nails with one stroke and without imposing heavy labor 25 upon the workman.

The accompanying drawings show the invention in its preferred practical form, but the invention is to be understood as fully commensurate with the appended claims.

30 Having thus fully described the invention, what I claim as new and desire to secure by Letters Patent is:

1. In a nailing machine, an upright guide tube provided at its lower end with a guide block, a plunger mounted for vertical reciprocation in said tube and provided at its lower end with a driving pin, a feed passage communicating with the interior of the tube from one side thereof above the guide block, a valve 35 cooperating with the feed passage and embodying fingers projecting into the feed passage from opposite sides thereof, and at different points in the length of the passage, means for laterally reciprocating said valve to feed nails one at a time through the passage to the guide block, and a magazine superimposed upon the feed passage and adapted to contain nails in substantially horizontal parallel relation to one another, said 40 magazine being detachably mounted with respect to the feed passage and having a removable side wall whereby the magazine may be removed from the feed passage and laid flat with the removable wall removed 45 to allow of easy filling of the magazine.

2. In a nailing machine, an upright guide tube provided at its lower end with a guide block, a plunger mounted for vertical reciprocation in said tube and provided at its 60 lower end with a driving pin, a feed passage communicating with the interior of the tube from one side thereof above the guide block, a valve cooperating with the feed passage and embodying fingers projecting into the feed passage from opposite sides thereof,

and at different points in the length of the passage, means for laterally reciprocating said valve to feed nails one at a time through the passage to the guide block, and a magazine superimposed upon the feed passage to supply nails to the valve, and spring arms for supporting the tubular guide in upstanding position, said arms being sufficiently rigid to normally support the tubular guide and its guide block free from engagement with the floor, but being sufficiently resilient to permit the guide block to engage with the floor when the plunger is moved downwardly to drive a nail positioned in the guide block.

3. In a nailing machine, an upright guide tube provided at its lower end with a guide block, a plunger mounted for vertical reciprocation in said tube and provided at its lower end with a driving pin, a feed passage communicating with the interior of the tube from one side thereof above the guide block, a valve cooperating with the feed passage and embodying fingers projecting into the feed passage from opposite sides thereof, and at different points in the length of the passage, means for laterally reciprocating said valve to feed nails one at a time through the passage to the guide block, a magazine superimposed upon the feed passage to supply nails to the valve, means in the feed passage to engage with the heads of the nails as they are fed from the valve to tilt the nails and cause them to fall with their points down, and enter the guide block in 100 upstanding position with the heads up, and means on the guide tube adapted for co-operation with means carried by the shoe of the workman whereby the machine may be propelled along the supporting surface 105 by the foot of the workman.

4. In a nailing machine, an upright guide tube provided at its lower end with a guide block, a plunger mounted for vertical reciprocation in said tube and provided at its lower end with a driving pin, a feed passage communicating with the interior of the tube from one side thereof above the guide block, a valve cooperating with the feed passage and embodying fingers projecting into the feed passage from opposite sides thereof, and at different points in the length of the passage, means for laterally reciprocating said valve to feed nails one at a time through the passage to the guide block, a magazine superimposed upon the feed passage to supply nails to the valve, and spring arms for supporting the tubular guide in upstanding position, said arms being sufficiently rigid to normally support the tubular guide and its guide block free from engagement with the floor, but being sufficiently resilient to permit the guide block to engage with the floor when the plunger is moved downwardly to drive a nail positioned in the guide block,

and casters carried by the spring arms to permit them to readily traverse the surface on which they are supported.

5. In a nailing machine, an upright guide tube provided at its lower end with a guide block, a plunger mounted for vertical reciprocation in said tube and provided at its lower end with a driving pin, a feed passage communicating with the interior of the 10 tube from one side thereof above the guide block, a valve cooperating with the feed passage and embodying fingers projecting into the feed passage from opposite sides thereof and at different points in the length of the 15 passage, means for laterally reciprocating said valve to feed nails one at a time through the passage to the guide block, a magazine superimposed upon the feed passage to supply nails to the valve, spring arms for 20 supporting the tubular guide in upstanding position, said arms being sufficiently rigid to normally support the tubular guide and its guide block free from engagement with the floor, but being sufficiently resilient to 25 permit the guide block to engage with the floor when the plunger is moved downwardly to drive a nail positioned in the guide block, casters carried by the spring arms to permit them to readily traverse the sur-

face on which they are supported, and 30 means on the guide tube adapted for co-operation with means carried by the shoe of the workman, whereby the machine may be propelled along the supporting surface by the foot of the workman.

35 6. In a nailing machine, an upright guide tube provided at its lower end with a guide block, a plunger mounted for vertical reciprocation in said tube and provided at its lower end with a driving pin, a feed passage 40 communicating with the interior of the tube from one side thereof above the guide block, a nail valve cooperating with the feed passage, means for operating said valve to feed nails one at a time through the passage to 45 the guide block, and a magazine superimposed upon the feed passage to supply nails to the valve, and resilient means for normally supporting the tubular guide and its 50 guide block free from engagement with the floor, said resilient means being sufficiently yielding to permit the guide block to engage with the floor when the plunger is forced downwardly to drive a nail positioned in the 55 guide block.

In testimony whereof I have signed the foregoing specification.

PATRICK GAVIN.
